US00D658186S

(12) **United States Design Patent**
Akana et al.

(10) **Patent No.:** US D658,186 S
(45) **Date of Patent:** ** Apr. 24, 2012

(54) **COVER**

(75) Inventors: **Jody Akana**, San Francisco, CA (US); **Bartley K. Andre**, Menlo Park, CA (US); **Jeremy Bataillou**, San Francisco, CA (US); **Daniel J. Coster**, San Francisco, CA (US); **Daniele De Iuliis**, San Francisco, CA (US); **Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Portola Valley, CA (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zorkendorfer**, San Francisco, CA (US)

(73) Assignee: **Apple Inc.**, Cupertino, CA (US)

(**) Term: **14 Years**

(21) Appl. No.: **29/375,197**

(22) Filed: **Sep. 17, 2010**

(51) **LOC (9) Cl.** **14-02**

(52) **U.S. Cl.** **D14/440**

(58) **Field of Classification Search** D14/439, D14/440, 345, 341-344, 346, 371, 125-129, D14/327, 248; 206/320, 576, 305, 215, 232, 206/524, 425, 472, 224, 312, 387.13, 307, 206/387.1, 756; D3/286, 283, 295, 273, D3/303, 247, 215, 245, 232, 900, 249, 201, D3/276, 294, 301, 319, 203.1, 323, 227; 224/929; 708/110; 190/109, 100, 119, 901; 361/683, 725, 681, 686, 679; 229/87.5, 67.1, 229/800; 220/522, 4.23; 345/169, 104, 156, 345/168, 173, 179, 672, 174; 150/147, 135; 402/2, 70-79, 500-502; 281/45, 38, 31, 281/29, 19.1, 34; D19/3, 26, 27, 33, 75, D19/86, 22, 90, 59, 60, 78, 83; D18/7, 17, D18/18; 383/97, 4, 110; 178/18.03, 18.01; 349/12; 428/332; D6/632, 407, 596, 601, D6/310, 611, 502, 583, 582, 595; 248/458;

(57) **CLAIM**

The ornamental design for a cover, as shown and described.

DESCRIPTION

An example of the type of device that may be used with the present invention is the electronic devices disclosed in U.S. Appl. Nos. 29/353,307 and 29/354,599.

FIG. 1 is a front perspective view of a cover showing our new design;

FIG. 2 is a rear perspective view thereof;

FIG. 3 is a front view thereof;

FIG. 4 is a rear view thereof;

FIG. 5 is a bottom view thereof;

FIG. 6 is a top view thereof; and,

FIG. 7 is a side view thereof, the opposite side being a minor image thereof.
